UNITED STATES PATENT OFFICE

173,284

RESPIRATOR MOTIVATING UNIT

Marvin H. Polzin, Wheatridge, and John A. Geer
and Fred E. Fowler, Boulder, Colo.

Application March 24, 1954, Serial No. 29,676

Term of patent 14 years

(Cl. D83—1)

To all whom it may concern:

Be it known that we, Marvin H. Polzin, John A. Geer, and Fred E. Fowler, have invented a new, original, and ornamental Design for a Respirator Motivating Unit, of which the following is a specification, reference being had to the accompanying drawing, forming a part hereof.

Fig. 1 is a perspective view of the top and one side of a respirator motivating unit embodying our new design;

Fig. 2 is a top plan view thereof; and

Fig. 3 is a perspective view taken from the side opposite that shown in Fig. 1.

The ends of the unit not shown are substantially plain.

We claim:

The ornamental design for a respirator motivating unit, substantially as shown and described.
